UNITED STATES PATENT OFFICE.

JOSEPH PAGLIARUL, OF ELGIN, ILLINOIS, ASSIGNOR TO JOSEPH E. SMYTH, OF CHICAGO, ILLINOIS.

WIRE STRAIGHTENING AND TENSIONING DEVICE.

1,237,547.

Specification of Letters Patent. Patented Aug. 21, 1917.

Application filed January 10, 1917. Serial No. 141,533.

To all whom it may concern:

Be it known that I, JOSEPH PAGLIARUL, a citizen of the United States, residing in the city of Elgin, county of Kane, and State of Illinois, have invented certain new and useful Improvements in Wire Straightening and Tensioning Devices, of which the following is a specification.

My invention relates to wire straightening and tensioning devices, and refers more particularly to such devices as may be employed in wire stitching machines.

Among the salient objects of the invention are, to provide an improved straightening and tensioning device in which the straightening and tensioning means are arranged on a common unitary support; to provide improved means for adjusting and securing the various parts in desired position; to provide a single means for straightening the wire so as to curvature in two planes at an angle to each other and, in general, to provide an improved wire straightening and tensioning device of the character referred to.

My invention relates to the matters hereinafter described, and more particularly pointed out in connection with the accompanying drawings, in which—

Figure 1 is a side elevation of the device in its angular relation to the wire stitching machine a portion of which is shown for the sake of clearness;

Fig. 2 is a side elevation similar to Fig. 1, but partly in section; and

Fig. 3 is a front elevation.

Referring to the drawings, the device comprises a wire straightening stud 10, the spring-pressed adjustable tension guide 11, and the delivery guide 12, all mounted in and carried by a rectangular block 13 secured to the front of the arm 14 projecting from the lower side of the main frame casting (not shown). The delivery guide 12 is a round pin secured in the block 13 rigidly by means of a pin 15 and is provided with a transverse hole 16 in line with the wire, and performs no straightening function. The adjustable tension plunger 11 is formed from a piece of round steel with a reduced neck portion 17 sliding within a cylindrical hole in the block 13, and the lower end of the plunger is still further reduced in diameter to accommodate the coil compression spring 18 which is located in the cylindrical bore 19 co-axial with the upper bore and neck 17. 55 The lower end of the plunger is threaded to accommodate an adjusting nut 20 between which and the end of the spring is interposed a washer 21. The action of the spring which is compressed between the washer 21 and the bottom of the bore 19 is such as to force the plunger 11 in a downward direction and clamp the wire against the upper face of the block 13, the wire passing through a transverse aperture 22 in the plunger located just below the shoulder at the end of the neck 17. The wire-straightening guide 10 is also formed from a cylindrical piece of steel and is rotatably mounted within the block 13. The lower end of the 70 guide 10 is threaded and is furnished with an adjusting nut 23, the latter being formed with a collar 24 which engages a notch 25 in the block 13 and enables the plunger 10 to be adjusted up and down longitudinally. 75 The extreme lower end of the guide 10 is also drilled out transversely to accommodate the reduced end of the small arm 26 which is riveted therein, and forms a convenient handle with which to set the guide in its required angular position. The upper end of the plunger 10 is drilled out transversely and the outer mouth of the hole is formed V-shaped, as shown at 27 in order to prevent damage to the wire as it enters. In 85 practice the wire is threaded through transverse holes in the three members 10, 11, and 12, and if it is found that the wire as it passes out of the hole 16 in the guide 12 has an upward bend, the guide 10 is lowered by 90 means of the adjusting nut 23 so as to bring the inner end of the hole 27 below the apex 28 which is formed by the meeting edges of the upper flat surface 29 of the block 13 and the other beveled surface 30. The wire will 95 thus be given a downward bend at that point and after one or two trials and adjustments of the nut 23, the wire can be made to travel out of the final guide 16 so as to lie in an inclined plane precisely in line with the axis 100 of the hole 26. In some cases, however, the wire, although it appears to be straight as viewed from the front of the machine in a horizontal direction, actually may be bowed so as to depart from the desired vertical 105 plane of travel. This may be corrected by swinging the guide 10 bodily by means of the small handle 16 so as to place the hole 27

at an angle with the direction of the wire, thus causing it to bend slightly. When the guide 10 has been properly adjusted to cause the wire to pass out of the straightener in a 5 sufficiently straight direction, it is locked in place by means of the set screw 31. The frictional drag on the wire as it passes through the wire-straightening device may be lessened or increased by adjusting the nut 10 20 which causes the end of the plunger 11 to press the wire more or less tightly against the upper face 29 of the top of the block 13. It will be noticed that the hole 22 is relatively long compared with the diameter of 15 the plunger 11 which makes it possible to use the flaring mouth of the hole 22 as a means for bending the wire in an upward direction in case the wire is found to curve downwardly as it passes from out the hole 20 26. This is of course made possible by raising the guide 10 a sufficient distance to bring the hole 27 above the plane of the surface 19 a sufficient distance to cause the wire to bend upwardly as it enters the hole 22 in the 25 spring-pressed plunger 11.

It will be readily understood by those skilled in this art that the apparatus herein shown and described is capable of variation and modification as to its details of structure 30 and organization to a considerable extent without departing from the principles of operation involved or lessening the efficiency of the apparatus for its described and intended purposes. Hence it is to be understood that 35 the invention is not limited to the exact constructions and relative arrangements of the coöperating parts otherwise than as clearly pointed out in the appended claims.

I claim—

40 1. A wire straightening device, comprising a frame member, a longitudinally adjustable guide member rotatably mounted in said frame member and having a transverse aperture for the passage of the wire, said 45 frame member having guiding means for said wire adjacent the aperture in said guide member, and means for fixing the angular and longitudinal position of said guide

member with reference to said frame member and said guiding means.

50

2. In wire straightening mechanism, the combination of a frame provided with a pair of guides for the wire, one of said guides being bodily adjustable with reference to the other guide member to bend the wire in the 55 direction of said bodily adjustment, and angularly adjustable within said frame to bend the wire in the direction of said angular adjustment.

55

3. In wire straightening and tensioning 60 device, the combination of a frame member provided with means adapted to deliver the wire in a straight line from said frame member, and a guide plunger having a transverse opening of a length greater than the distance across said opening, said guide plunger being bodily adjustable to bring said opening to one side of said straight line and angularly adjustable to establish an angle between the axis of said opening and 65 said straight line, and means for fixing the position of said plunger in adjusted position.

70

4. In wire straightening and tensioning device, the combination of a frame member, a spring-pressed non-rotatable guide member carried by said frame member provided with a longitudinal guiding aperture coaxial with the desired direction of travel of the wire and adapted to press the wire into frictional engagement with said frame member, and a guiding plunger provided with a transverse wire conduit longitudinally adjustable in said frame member to bring the axes of said conduit and said guiding aperture into different planes, and rotatably 80 mounted in said frame member to cause the axis of said conduit to intersect the plane of 85 the angle of travel of the wire.

75

5. In a wire straightening and tensioning 90 device, comprising, a frame, a longitudinally adjustable and rotatively mounted member having a wire passage therein, guiding means adjacent to said passage, and means for securing the movable member with respect to the frame and the guiding means. 95

JOSEPH PAGLIARUL.
